LOUIS H. GILBERT, OF HARTFORD, CONNECTICUT

COMPOSING STICK

Application filed March 21, 1929. Serial No. 348,730.

This invention relates to a device for, and method of, positioning type casting matrices within a composing stick and for compensating the position of the composing stick when 5 a line of matrices mounted within the composing stick does not occupy the full length of the composing stick.

An object of the present invention is to provide simple means to approximately center 10 type casting matrices in a composing stick and then to so position the composing stick, when located for casting, that the printing slug will be cast with the type formed by the matrices located exactly centrally of the slug. 15 A further object of the invention is to improve the construction of a composing and casting stick and locating means therefor in a slug casting machine so that a line of type of any length on the printing slug will be accurately centered relative to the slug, this object being accomplished without the necessity of calculation and judgment of the operator.

With these and other objects in view, my 20 invention includes the features of construction and operation set forth in the following 25 specification and illustrated in the accompanying drawings.

In the accompanying drawings annexed hereto and forming a part of this specification, I have shown by invention embodied in a composing and casting stick for a well known form of typograph machine, but it will be understood that the invention can be otherwise embodied and that the drawings 30 are not to be construed as defining or limiting the scope of the invention, the claims appended to this specification being relied upon for that purpose.

In the drawings—
40 Fig. 1 is a plan view of a composing and casting stick with type casting matrices positioned therein;

Fig. 2 is a similar view of the composing and casting stick with the matrices approximately centered by the interposition of blank matrices or quadrats at opposite ends;

Fig. 3 is an isometric view of the underside of the composing and casting stick showing the type casting faces of the matrices;

50 Fig. 4 is a plan view of the composing and

casting stick located in position for the casting operation in a printing slug casting machine by means forming part of the present invention;

Fig. 5 is a side elevation of the parts shown 55 in Fig. 4; and

Fig. 6 is a view in elevation taken from the left hand end of Fig. 4.

In the above mentioned drawings I have shown but one embodiment of the invention 60 which is now deemed preferable, but it is to be understood that changes and modifications may be made within the scope of the appended claims without departing from the spirit 65 of the invention.

In casting lines of type it is desirable particularly in casting lines of variable or fractional length that some simple and accurate means be provided for centering the type casting matrices within the length of the composing stick so that when the line of type is cast the printing faces of the type will be accurately centered along the slug. Heretofore this operation has been accomplished manually by first composing the line with 70 matrices as indicated in Fig. 1, and then applying blank matrices or quadrats of equal thicknesses at opposite ends until the entire line is filled up to the zero graduation on the composing stick. It will be apparent from 75 this that much depends, in order to obtain accurately centered type on the printing slug, upon the care and judgment of the compositor in arranging the matrices within the composing stick prior to clamping them in 80 position and then casting them in the usual manner. The present device and method facilitate this centering or justifying operation to obtain the type faces disposed centrally 85 of the slug, and eliminates all skill and judgment on the part of the compositor in accomplishing it.

In carrying out the method of the present invention the type casting matrices are 90 roughly centered within the composing stick 95 by placing quadrats of similar thickness on opposite ends of the line of matrices. With the matrices clamped therein the composing stick is then positioned in the line casting machine and is accurately positioned for the 100

casting operation by stops on the composing stick cooperating with members on the casting machine. One of the stops is fixed in position upon the composing stick and the other stop has its position varied by variations in length of the line of type to be cast. Preferably, and as shown, the variably positioned stop is mounted on the clamping block for the matrices so that it is always a predetermined distance from an end of the combined matrices and quadrats.

Referring more in detail to the figures of the drawings it will be seen that matrices 10 having type casting faces thereon are positioned in the composing stick 11 in the usual manner. These matrices 10 usually, and as indicated in Fig. 1, do not completely fill the composing stick 11, but leave a space unfilled as indicated adjacent the graduation 20.3. This space is then filled by blank matrices or quadrats 12 having no type casting faces thereon. Blank matrices 12 of equal thickness are applied to opposite ends of the composed set of type casting matrices 10 so that these type casting matrices 10 will be disposed approximately centrally of the length of the composing stick 11. Graduations 13 are applied to the composing stick 11 to indicate the particular size or thickness of blank matrix 12 to be applied to each end of the composed line of matrices to approximately fill the composing stick. As indicated these graduations are double spaced so that the graduations opposite the space left at one end to be filled will correspond to the size of the quadrats at each end. With these blank matrices applied at opposite ends of the line of composed type casting matrices 10 it will be noted that a slight fractional amount will still remain to be taken up by the clamping block 14 between the end of the quadrat 12 and the zero graduation 13. The clamping block 14 is now forced against the matrix at one end and thus securely retaining all of the matrices in position in the usual manner.

This composing stick 11 is now ready to be applied to the casting machine 15 in position for casting. It will be noted however that the composed matrices 10 are not exactly centered axially of the composing stick 11 and thus if the composing stick 11 is positioned against the usual stop 16 on the casting machine 15 the line of type cast upon the slug will not be disposed exactly centrally of the slug. Means are therefore provided to adjust the axial position of the composing stick 11 when positioned for casting on the machine 15 to compensate for the small error not compensated for by the quadrats 12 at the opposite ends of the matrices 10. A stop 17 in the form of a pin or other form of integral projection positioned along one side of the composing stick 11 is adapted to contact with one end of a lever 18 pivotally

mounted upon the casting machine 15 closely adjacent the slideway 19 within which the composing and casting stick 11 is mounted. Moving this composing stick 11 along the slideway 19 the stop or pin 17 upon the composing stick 11 is caused to contact with one arm of the lever 18 and oscillates the lever. Mounted adjacent the pivotally mounted lever and adapted to slide in a direction parallel to the axis of the slideway 19 is a slide 20. One end of this slide 20 contacts with a stop 21 outstanding from one side of the clamping block 19 on the composing stick 11. Movement of the composing stick 11 forwardly within its slideway 19 will therefore not only force the pin 17 against one arm of the pivoted lever 18 but will also cause movement of the slide 20 by engagement of the slide 20 with the stop 21 on the clamping block 14. The slide 20 is therefore moved to a position determined by the particular position of the clamping block 14 until the composing stick 11 is held fast by cooperative action between the slide 20 and lever 18 engaging the fixed and movable stops 17 and 21 on the composing stick and its clamping block. The position, therefore, of the composing stick 11 will be compensated slightly for the fraction of the space within the composing stick 11 not filled with matrices 10 and the type casting faces will be accurately centered relative to the casting mold for the slug provided in the casting machine.

I claim:

1. A justifying device for composing and casting sticks comprising a fixed stop mounted on said stick, a clamping block for the matrices within said stick, a stop mounted on said clamping block, said stops being adapted for engagement by cooperating means when said stick is in position for casting, whereby the longitudinal position of the stick will be determined by the relative position of said stops.

2. A justifying device for composing and casting sticks comprising a fixed stop mounted intermediate the length of said stick, a clamping block for the matrices within said stick adjacent one end of said stick, a stop mounted on and movable with said clamping block, and means engaging said stops when said stick is in position for casting, whereby the longitudinal position of said stick will be determined by the position of said clamping block and stops.

3. A justifying device for composing and casting sticks comprising a fixed stop mounted on said stick, a clamping block for the matrices within said stick, an adjustable stop mounted on and outstanding from said block, and means engaging said stops and determining the axial position of said stick when in casting position.

4. A centering device for composing and casting sticks comprising in combination, a

composing and casting stick having spaced stops thereon, the position of one of said stops being determined by the length of the matrices within said stick, a lever pivotally mounted on a casting machine engaging one stop when said stick is positioned for casting, and a slide on the casting machine engaging the second stop and the opposite arm of the lever, whereby the axial position of said stick 5 when positioned for the casting operation is governed by the position of said stops.

5. A centering device for composing and casting sticks comprising in combination, a composing and casting stick having spaced stops thereon, one of said stops being fixed and the other determined by the length of matrices within said stick, a lever pivotally mounted on the casting machine engaging one stop when said stick is positioned for casting, and a slide on the casting machine engaging the second stop and the opposite arm of the lever, whereby the axial position of said stick is governed by the position of said stops.

25 6. A centering device for composing and casting sticks comprising in combination, a composing and casting stick having a fixed stop thereon, an adjustable stop thereon, the position of which is governed by matrices in said stick, a lever pivotally mounted on a casting machine engaging one stop when said stick is positioned for casting, and a slide on the casting machine engaging and being disposed between the adjustable stop and the 30 opposite arm of said lever, whereby the axial position of said stick is governed by the position of said stops.

7. A centering device for composing and casting sticks comprising in combination, a 40 composing and casting stick having a fixed stop thereon, an adjustable stop thereon, a lever pivotally mounted on the casting machine engaging one of the stops when said stick is positioned for casting, and a slide 45 on the casting machine engaging the other stop and the opposite arm of the lever, whereby the axial position of said stick is governed by the position of said stops.

8. A centering device for composing and 50 casting sticks comprising in combination, a composing and casting stick having a fixed stop thereon, a stop carried by and movable with the clamping block of said stick, a lever carried by the casting machine used with said 55 stick, one arm of said lever being adapted to contact with said fixed stop on said stick, a slide on said casting machine movable parallelly with said stick and adapted to contact with and be moved by the movable stop on 60 said stick against the opposite arm of said lever, whereby the axial position of said stick will be governed by the position of said clamp block.

9. A centering device for composing and 65 casting sticks comprising in combination, a

composing and casting stick having a fixed stop thereon, a stop carried by and movable with the clamping block of said stick, a pivotally mounted lever carried by the casting machine used with said stick, one arm of which is adapted to contact with said fixed stop, a slide on said casting machine adapted to contact with and be moved by the movable stop to a position against the opposite arm of the lever, whereby the axial position of 70 said stick will be governed by the position of said clamp block.

10. A justifying device for composing and casting sticks comprising in combination, a fixed stop on said stick, an adjustable stop thereon the position of which is determined by the length of the line of matrices in said stick, and means engaging said stops for determining the longitudinal position of said stick when in position for casting.

85 11. A justifying device for composing and casting sticks comprising in combination, a composing stick having a plurality of matrices therein, quadrats of equal thickness at opposite ends of said matrices, means to clamp said matrices and quadrats in position in said stick, a fixed stop on said stick, a second stop on said stick the position of which is determined by the length of said matrices and quadrats, and means engaging 90 said stops for determining the longitudinal position of said stick when in position for casting.
